CLAIM

The ornamental design for the snips, as shown and
described.

DESCRIPTION

FIG. 1 is a top plan view of a snips showing our new design;
FIG. 2 is a rear elevational view thereof;
FIG. 3 is a bottom plan view thereof;
FIG. 4 is a front elevational view thereof;
FIG. 5 is a left side elevational view thereof;
FIG. 6 is a right side elevational view thereof;
FIG. 7 is a front elevational view thereof in an open position;
FIG. 8 is a top plan view of a second embodiment of the
snips shown in FIG. 1;
FIG. 9 is a rear elevational view thereof;
FIG. 10 is a bottom plan view thereof;
FIG. 11 is a front elevational view thereof;
FIG. 12 is a left side elevational view thereof;
FIG. 13 is a right side elevational view thereof; and,
FIG. 14 is a front elevational view thereof in an open
position.

The broken line showing in the figures is for illustrative
purposes only and forms no part of the claimed design.
